CLAIM

The ornamental design for an archery bow cam, as shown
and described.

DESCRIPTION

FIG. 1 is a left side view of an archery bow cam showing my
new design;

FIG. 2 is a left side perspective view thereof;

FIG. 3 is a left side view thereof;

FIG. 4 is a right side view thereof;

FIG. 5 is a front view thereof;

FIG. 6 is a rear view thereof;

FIG. 7 is a top view thereof; and,

FIG. 8 is a bottom view thereof.

The broken lines are for illustrative purposes only and form
no part of the claimed design.
